UNITED STATES PATENT OFFICE

171,301

REVERSIBLE FLOOR MAT

Thomas C. Kravitz, University Heights, Ohio, assignor to Anchor Rubber Products, Inc., Cleveland, Ohio, a corporation of Ohio

Application June 13, 1952, Serial No. 20,177

Term of patent 14 years

(Cl. D9—6)

To all whom it may concern:

Be it known that I, Thomas C. Kravitz, a citizen of the United States, residing at University Heights, county of Cuyahoga, and State of Ohio, have invented a new, original, and ornamental Design for a Reversible Floor Mat, of which the following is a specification, reference being had to the accompanying drawings, forming a part hereof:

Fig. 1 is a plan view of one side of a reversible floor mat showing my new design;

Fig. 2 is a plan view of the other side of the mat;

Fig. 3 is a fragmentary cross-sectional view, on an enlarged scale, taken on the line 3—3 of Fig. 1, and

Fig. 4 is a fragmentary cross-sectional view, on an enlarged scale, taken on the line 4—4 of Fig. 2.

I claim:

The ornamental design for a reversible floor mat, substantially as shown.

THOMAS C. KRAVITZ.
